(**) Term: **14 Years**

(57) **CLAIM**

(21) Appl. No.: **29/166,932**

The ornamental design for a computer keyboard including a three-dimensional input device attached thereto, as shown and described.

(22) Filed: **Sep. 6, 2002**

DESCRIPTION

(30) **Foreign Application Priority Data**

Mar. 12, 2002 (DE) 4 02 02 328

FIG. 1 is a top plan view,

(51) LOC (7) Cl. **14-02**

FIG. 2 is a front view,

(52) U.S. Cl. **D14/398; D19/60**

FIG. 3 is a view from below,

(58) **Field of Search** D14/391-398,

FIG. 4 is a rear view,

D14/400; D18/1, 2, 7; 200/5 A, 5 R, 6 A,
6 R; 235/145 A, 145 R; 178/17 A, 17 C;
341/22, 23; 345/168, 160; 400/486, 488,
489, 492, 484, 485; D19/60

FIG. 5 is a left side elevation,

(56) **References Cited**

FIG. 6 is a right side elevation; and,

FIG. 7 is a perspective view.
